(57) **CLAIM**

The ornamental design for a tray for a slicer, as shown and described.

DESCRIPTION

FIG. 1 is a perspective view of the tray for a slicer shown in conjunction with a slicer;
 FIG. 2 is a left side view of the tray for a slicer of FIG. 1;
 FIG. 3 is a right side view of the tray for a slicer of FIG. 1;
 FIG. 4 is a rear view of the tray for a slicer of FIG. 1;
 FIG. 5 is a front view of the tray for a slicer of FIG. 1;
 FIG. 6 is a top view of the tray for a slicer of FIG. 1; and,
 FIG. 7 is a bottom view of the tray for a slicer of FIG. 1.
 The broken line portions of the drawings are for illustrative purposes only and do not constitute part of the claimed design.
